UNITED STATES PATENT OFFICE.

OBERLIN SMITH, OF BRIDGETON, NEW JERSEY, ASSIGNOR OF ONE-HALF TO
GEORGE DRAPER & SONS, OF HOPEDALE, MASSACHUSETTS.

LOOM.

SPECIFICATION forming part of Letters Patent No. 569,805, dated October 20, 1896.

Application filed August 9, 1895. Serial No. 558,718. (No model.)

To all whom it may concern:

Be it known that I, OBERLIN SMITH, of Bridgeton, county of Cumberland, State of New Jersey, have invented an Improvement in Looms, 5 of which the following description, in connection with the accompanying drawings, is a specification, like letters on the drawings representing like parts.

This invention in looms has especial reference to devices having openings through which the warp-threads are passed, and which may be called "warp devices," the same being employed to fulfil the function of heddles for the shedding of the warp-threads and also 15 for the detection and stopping of the loom upon the occurrence of broken warp-threads, or employed solely for the detection and stopping of the loom upon occurrence of broken warp-threads.

20 My invention consists in bending said devices at or adjacent the openings and transversely to the line of travel of the warp-threads passed through said openings so that the said threads may pass nearly or quite 25 straight through the said openings and from one to the other side of the said devices without bending the threads, to thereby save wear of the threads due to the bending of the same in passing through the openings, as heretofore, and also to avoid the tendency of the 30 threads so bent to twist the devices out of their true positions.

35 My invention further consists in the combination of such devices with suitable heddle-operating and stop-motion devices, to be described.

40 In the drawings, Figure 1 is a vertical cross-section of a loom provided with warp devices embodying my invention, the same showing sufficient parts to enable the invention to be clearly understood; Fig. 2, a side view of one 45 of the warp devices broken off at its lower end, with a thread passed through the opening therein; Fig. 3, a view looking at the edges of several devices arranged one close to another and with their lower ends broken off; and Fig. 4 an enlarged sectional detail on the dotted line x x , Fig. 3, showing the passage of the threads through the openings in 50 my improved devices.

In the embodiment of my invention selected

for illustration and herein shown in the drawings the frame A, the uprights or standards A¹, the cam-shaft A², the lay A³, carrying a reed, the whip-roll A⁴, the stands B, the rolls or rods b, journaled therein, the heddle-frames, comprising the top and bottom connected bars a' a, pulleys a⁶, straps a⁷ a⁸, the lower connecting-straps a⁹ a¹⁰, the actuating-levers a¹¹ a¹², pivoted at a¹³, and the cams a¹⁴ a¹⁵, the feelers 60 f', on and rocked by shaft f, the cam G, controller-lever g, and shipper-handle A⁶ of the stop-motion are and may be as in looms of usual construction, such, for instance, as illustrated in United States Patent No. 536,969, 65 issued April 2, 1895, to Charles F. Roper, to which reference may be had, like letters representing like parts, the same coöperating as fully shown and described in said patent. In the said patent the heddles d therein shown 70 are strips of flat metal, the warp-threads traveling in the planes of the heddles being necessarily turned or bent in order to pass through the openings 2 in the said heddles, this turning or bending of the threads giving rise to 75 unnecessary friction and sometimes, when the warp-threads are under sufficient tension, operating to twist the heddles more or less from their normal positions.

80 In my present invention, as herein illustrated, I employ heddles d, used also, as stated, for the purposes corresponding to the devices similarly lettered in the patent referred to; but instead of employing flat metallic heddles, as in the said patent, in this present invention the said devices are crimped or bent longitudinally, that is, in the direction transversely to the direction of travel of the warp-threads through the openings 2 therein, to thereby offset the opposite edges of the said 85 devices adjacent said openings to enable the warp-threads to pass straight through the openings, as best shown in Fig. 4. These crimps or bends are shown as extended throughout the entire lengths of the heddles, 90 but it is evident that the length of the crimps or bends may be made as desired or necessary and the degree of crimping or bending may also be varied to cause more or less offset at the opposite edges of the devices, as 95 100 may be found necessary or desired.

My invention is not limited to any particu-

lar shape or construction nor to the use of any particular material, the gist of my invention consisting in the crimping or bending of the device, having an opening through which 5 a warp-thread is passed, so that opposite sides or faces of the said device at opposite sides of the said opening shall be in different planes, to thereby enable a thread to be passed through said opening without unduly 10 bending the same, whether such devices are used for shedding the warp-threads and detecting broken warp-threads or for either shedding or detecting, as the case may be.

Having described one embodiment of my 15 invention, and without limiting myself as to details, what I claim, and desire to secure by Letters Patent, is—

1. The described device for looms, it having an opening for the passage therethrough 20 of a warp-thread, said device being crimped or bent longitudinally and throughout its entire length whereby the portions at opposite sides said opening are offset to provide a straight passage of the thread through said opening, and at the same time enable two or 25 more of said devices when closely arranged side by side to have free and independent longitudinal movement, substantially as described.

30 2. In a loom, the combination with a frame, and heddle-moving mechanism, of the heddle-frames, and devices carried thereby and provided with openings for the warp-threads, said devices being crimped or bent longitudi-

nally for their entire lengths to offset portions at opposite sides of said opening to provide substantially straight passage of the warp-threads through said openings, substantially as described.

3. In a loom, the combination with a frame, 40 and a lay, of devices provided with openings for the warp-threads said devices being crimped or bent longitudinally throughout their entire lengths to thereby offset portions at opposite sides said openings to provide a 45 substantially straight passage of the warp-threads therethrough, and a stop-motion, and its feeler coöperating with the said devices, substantially as described.

4. In a loom, the combination with a frame, 50 a lay, the heddles having openings for the passage of the warp-threads, said heddles being bent or crimped longitudinally throughout their entire lengths to thereby offset portions at opposite sides of said openings, off- 55 set to provide substantially straight passage of the said threads, mechanism to move said heddles to shed the threads, a warp stop-motion and its feeler coöperating with said heddles, substantially as described.

In testimony whereof I have signed my name to this specification in the presence of two subscribing witnesses.

OBERLIN SMITH.
